UNITED STATES PATENT OFFICE.

FRANK BROOKS HINE, OF EL PASO, TEXAS.

INK-FEEDER FOR PENS.

1,149,050.

Specification of Letters Patent. Patented Aug. 3, 1915.

Application filed February 6, 1915. Serial No. 6,484.

To all whom it may concern:

Be it known that I, FRANK B. HINE, a citizen of the United States, and a resident of El Paso, in the county of El Paso and 5 State of Texas, have invented a new and Improved Ink-Feeder for Pens, of which the following is a full, clear, and exact description.

This invention relates to writing pens 10 and deals particularly with a fountain attachment applied to the hollow of the pen for retaining and feeding ink to the tip of the pen, whereby a large number of words can be written with one dip of the pen into 15 an ink well.

The invention has for its general objects to improve and simplify the construction of ink feeding devices for pens so as to be reliable and efficient in use, comparatively 20 simple and inexpensive to manufacture, and so designed that they can be applied to a pen holder of ordinary construction and admit of the pen being applied or removed without the attachment interfering.

25 A further object of the invention is the provision of an ink feeding device which is made from a single piece of wire having a base or anchor portion so shaped as to fit in a pen holder, and formed with a conical 30 helical portion that lies within the hollow of the pen, and extending from this helix is a tip which is maintained in contact with the pen, whereby the ink feeds from the helix along the tip of the feeder to the tip of the 35 pen.

With such objects in view, and others which will appear as the description proceeds, the invention comprises various novel features of construction and arrangement of 40 parts which will be set forth with particularity in the following description and claims appended hereto.

In the accompanying drawing which illustrates one embodiment of the invention and 45 wherein similar characters of reference indicate corresponding parts in all the views, Figure 1 is a sectional view of a pen holder and pen with the ink feeding attachment applied thereto; Fig. 2 is a detail sectional 50 view on the line 2—2, Fig. 1; Fig. 3 is an end view of the pen and ink feeder; Fig. 4 is a perspective view of one form of the attachment; and Fig. 5 is a perspective view of another form.

55 Referring to the drawing, A designates an ordinary pen holder which has a bore 1

that contains a barrel 2 between which and the wall of the bore is inserted in the usual manner a pen B. The attachment C is removably mounted in the pen holder and can 60 be easily applied by a person of ordinary intelligence, as in fact the attachment is an article of manufacture which is capable of being attached to pen holders already in use, although it can be sold as a part of a 65 new pen holder.

The ink retaining and feeding attachment is made of a single piece of wire which has one end bent into an elongated or approximately rectangular loop 3, and connected 70 with the inner portion of this loop is a helix 4 of conical form with adjacent convolutions spaced apart, and at the apex of the helix is the other extremity 5 of the wire which forms a tip that extends in the general direction of the axis of the helix but is disposed in line with one side of the helix or coil so that the extremity or tip 5 will lie in contact with the under side of the pen when the attachment is applied to the 75 pen holder, as shown in Fig. 1. The loop 3 forms the attaching part of the ink feeder and is adapted to enter the slot 6 of the pen holder barrel 2. The slot 6 is usually provided in the barrel to provide resiliency 80 therefor, whereby the pen B can be readily inserted in the pen holder and still be firmly gripped. The loop 3 lies in a plane to one side of the axis of the helix and in line with that side opposite from the side of the 85 helix in which the tip 5 lies, so that by this construction the helix is in close proximity to the under side of the pen B, although contact of the helix with the pen is unessential, as it is only important that the tip 5 90 of the feeder be in contact with the pen. In use the helix holds a large mass of ink by the latter adhering to the convolutions of the helix, and this ink feeds gradually 95 to the pen point by means of the tip 5 of the feeder, and the adhesion of the ink to the helix prevents the ink from running down too freely. As the attachment has no connection with the pen but is merely in contact therewith the pen can be readily 100 removed from the holder A and a new pen inserted whenever desired. In the device shown in Fig. 4 the side members 7 and 8 of the loop 3 are relatively resilient, since the extremity 9 of the wire is not connected 105 with the member 8, and by reason of this the members 7 and 8 of the loop can spring 110

apart and tightly grip the barrel 1 of the pen holder. If desired, however, the members 7 and 8 of the loop 3 may be twisted together, as shown at 10, Fig. 5.

5 From the foregoing description taken in connection with the accompanying drawing, the advantages of the construction and method of operation will be readily understood by those skilled in the art to which 10 the invention appertains and while I have described the principle of operation, together with the device which I now consider to be the best embodiment thereof, I desire to have it understood that the device 15 shown is merely illustrative and that such changes may be made when desired as are within the scope of the appended claims.

Having thus described my invention, I claim as new and desire to secure by Letters 20 Patent:

1. The combination of a pen holder having a bore at one end and a pen holding barrel therein, and a pen disposed in the pen holder, with an ink-feeding device made 25 of a single piece of wire and formed into a loop anchored within the barrel of the pen holder and formed with a helix connected with the loop and disposed within the hollow of the pen, and a longitudinally extending tip on the end of the helix and bearing 30 against the under side of the pen adjacent the tip thereof.

2. An ink retaining and feeding attach-

ment for a pen holder and pen, comprising a single piece of wire bent into an elongated 35 attaching loop, a helix connected with the loop, and a longitudinally-extending tip on the end of the helix opposite from the loop.

3. An ink retaining and feeding attachment for a pen holder and pen, comprising 40 a single piece of wire having one extremity bent into an attaching portion, a helix connected with the attaching portion, and a tip formed by the other end of the wire and extending longitudinally from the end of 45 the helix opposite from the attaching portion, the said tip being eccentric to the axis of the helix and flush with the convolutions of the latter at one side, whereby the tip throughout its length and the convolutions 50 of the helix will be in contact with the under side of the pen.

4. An ink feeding attachment of the class described, comprising a single piece of wire 55 bent at one end into an elongated loop and having an intermediate portion bent into a helix tapering away from the loop, and the other end of the wire extending longitudinally from the apex of the helix.

In testimony whereof I have signed my 60 name to this specification in the presence of two subscribing witnesses.

FRANK BROOKS HINE.
